(57) **CLAIM**

The ornamental design for a dental themed playing card deck, as shown and described.

DESCRIPTION

FIG. 1 is a front elevational view of cards A-E and 1-8 from the "maxillary right" suit thereof;

FIG. 2 is a front elevational view of cards A-E and 1-8 from the "maxillary left" suit thereof;

FIG. 3 is a front elevational view of cards A-E and 1-8 from the "mandibular left" suit thereof;

FIG. 4 is a front elevational view of cards A-E and 1-8 from the "mandibular right" suit thereof;

FIG. 5 is a front elevational view of the "face" cards thereof;

FIG. 6 is a rear elevational view of each card of the deck of playing cards, showing my new design. Each card is of conventional thickness, with the top, bottom and sides being plain and unornamental, and forming no part of the claimed design; and,

FIG. 7 is a front elevational view of a "rules" card thereof.
